(57) **CLAIM**

I claim the ornamental design for an electrical wall plug, as shown and described.

DESCRIPTION

FIG. 1 is a front view showing an embodiment of the invention;

FIG. 2 is a rear view showing an embodiment of the invention;
FIG. 3 is a top, front view perspective showing an embodiment of the invention;

FIG. 4 is a top, rear perspective view showing an embodiment of the invention;

FIG. 5 is a right side perspective view showing an embodiment of the invention;

FIG. 6 is a left side perspective view showing an embodiment of the invention;

FIG. 7 is a bottom, rear view showing an embodiment of the invention;

FIG. 8 is a front, left, bottom perspective view showing an embodiment of the invention; and,

FIG. 9 is a front, right, perspective view showing an embodiment of the invention in use.

The broken lines shown in the drawings are included for the purpose of illustrating environmental structure and form no part of the claimed design.
